CLAIM

The ornamental design for a lighting fixture, as shown and described.

DESCRIPTION

FIG. 1 is a perspective view of a lighting fixture; FIG. 2 is a top view of a lighting fixture; FIG. 3 is a bottom view of a lighting fixture; FIG. 4 is a front view of a lighting fixture; FIG. 5 is a back view of a lighting fixture; FIG. 6 is a side view of a lighting fixture; and, FIG. 7 is another side view of a lighting fixture. The broken lines with the various embodiments of the claimed design and the spaces therein are included for illustrating environmental aspects only and form no part of the claimed design.
